[57] **CLAIM**

I claim the ornamental design for the rectangular jigsaw puzzle, as shown and described.

DESCRIPTION

FIG. 1 is a top plan view of a rectangular jigsaw puzzle showing my new design;
FIG. 2 is a bottom plan view thereof;
FIG. 3 is a right side elevational view thereof, the left side being identical; and,
FIG. 4 is a front elevational view thereof, the rear being identical.

1 Claim, 3 Drawing Sheets
